THE BANNER MACHINE COMPANY, OF COLUMBIANA, OHIO, A CORPORATION OF
OHIO.

COLLAPSIBLE CORE.

1,365,709.

Specification of Letters Patent. Patented Jan. 18, 1921.

Application filed May 31, 1919. Serial No. 301,133.

To all whom it may concern:

Be it known that we, EARL M. McCURRY and GEORGE R. BILGER, citizens of the United States, residing at Columbiana, in the county of Columbiana and State of Ohio, have invented a new and useful Collapsible Core, of which the following is a specification.

This invention relates to improvements in collapsible cores and mandrels, such as are used for building and vulcanizing tire casings.

The objects of the invention are to provide a collapsible core which may be quickly and easily assembled or knocked down and which when so assembled will be held firmly together, positive clamping means being provided for holding the separable sections together, frictional contact between the core sections and the clamping ring not being relied upon.

A further object is the provision of a simple, durable and efficient collapsible core and the invention also aims to generally improve devices of this character so as to render them more useful and commercially desirable.

With these objects in view the invention consists in the novel construction and arrangement of parts, hereinafter described, illustrated in the accompanying drawings, and particularly pointed out in the appended claim, it being understood that various changes in the form, proportions, size and minor details of construction may be made within the scope of the appended claim, without departing from the spirit or sacrificing any of the advantages of the invention.

The invention thus set forth in general terms is illustrated in the accompanying drawings forming part hereof, in which—

Figure 1 is a side elevation of the assembled core; and

Fig. 2 a section on an enlarged scale taken on a radial line through one of the studs.

A practical embodiment of the invention is disclosed in the accompanying drawings, forming a part of this specification in which similar numerals of reference indicate corresponding parts throughout the several views.

The core embodying the invention comprises an annulus formed of a plurality of

separable sections 1, each section comprising a body portion 2 substantially circular in cross section, and an inwardly extending flange 3 having an enlarged shouldered portion 4.

Each of the sections 1 of the annulus is provided upon its inner edge and near each end with a screw threaded stud 5, thus providing a stud at each side of each joint in the annulus.

The shouldered portion 4 when the sections are in the assembled condition forms complete annular abutments which shape the edges of the tire and coöperate with the mold sections in the usual manner. This shouldered portion is preferably provided in one side with an annular recess 6 designed to receive the annular flange 7 of the ring 8, said ring fitting snugly within the interior of the annulus, it being understood however that there is not a frictional contact between the ring and the annulus, excepting when the clamping nuts are adjusted as will be later described.

This ring is provided with a plurality of slots 9 arranged to receive the threaded studs 5 when the ring is placed in position within the annulus. In assembling the core the several sections of the annulus are placed together and the ring 8 inserted as shown in the drawings after which the clamping nuts 10, provided upon the threaded studs 5, are tightened, drawing the several sections of the annulus tightly against each other and against the periphery of the ring 8, thus locking the several sections of the annulus firmly together upon the ring.

When it is desired to remove the core from the tire the ring may be readily removed by loosening the clamping nuts 10, after which the ring is lifted out of the annulus allowing the core sections to be collapsed in the usual manner.

It will thus be seen that a very durable, efficient and simple collapsible core is provided wherein the parts are so arranged and formed that the operation of the assembling and knocking down, the core may be easily effected and the core sections positively held in firm relation to each other and to the rim when in the assembled condition.

Although the drawings and above specification disclose the best mode in which we have contemplated embodying our inven-

tion we desire to be not limited in the details of such disclosure, for, in the further practical application of our invention, many changes in form and construction may be 5 made, as circumstances require or experience suggests, without departing from the spirit of the invention, within the scope of the appended claim.

We claim:

- 10 A core of the character described, comprising an annulus formed of a plurality of sections having an annular recess at one inner edge, an annular ring adapted to be

located entirely within said annulus and having an annular shoulder around one 15 edge of its periphery arranged to engage said annular recess, and provided with radial notches, radial studs carried upon said sections and arranged to be received within said notches and means upon said studs for 20 drawing the sections toward the center of the annulus.

In testimony that we claim the above, we have hereunto subscribed our names.

EARL M. McCURRY.
GEORGE R. BILGER.
